UNITED STATES PATENT OFFICE.

LEO HOFMEISTER, OF MILWAUKEE, WISCONSIN.

FOOTWEAR.

1,356,717.

Specification of Letters Patent. Patented Oct. 26, 1920.

Application filed August 9, 1919. Serial No. 316,413.

To all whom it may concern:

Be it known that I, LEO HOFMEISTER, a citizen of the United States, and resident of Milwaukee, in the county of Milwaukee and State of Wisconsin, have invented new and useful Improvements in Footwear, of which the following is a description, reference being had to the accompanying drawings, which are a part of this specification.

10 The present invention relates to certain new and useful improvements in footwear and refers more particularly to a water-proof shoe especially adapted for use in dairies or any other place where the wearer 15 must stand in water to perform his various duties.

One object of this invention is to provide a light yielding water-proof shoe having removable and readily exchangeable soles and 20 heels.

Another object of this invention is to provide a shoe of the class described in which the bottom of the shoe upper will be integral with the sides thereof whereby to 25 insure the water-proofing of the shoe.

A further object of this invention is to provide a shoe of the class described in which the upper will have depending from the sides thereof integral side ribs forming 30 sole and heel receiving recesses adapted to receive an interchangeable sole and heel.

A still further object of this invention is to provide a shoe of the class described having sole and heel receiving recesses and 35 means for readily removably securing the sole and heel members in their respective recesses, whereby one shoe upper may be made to outlast a number of sole and heel members.

40 With the above and other objects in view which will appear as the description proceeds, my invention resides in the novel construction, combination and arrangement of parts substantially as hereinafter described and more particularly defined by the appended claims, it being understood that such changes in the precise embodiment 45 of the herein disclosed invention may be made as come within the scope of the 50 claims.

In the accompanying drawing I have 55 illustrated one complete example of the physical embodiment of my invention constructed according to the best mode I have so far devised for the practical application of the principles thereof, and in which:

Figure 1 is a side view of the lower portion of a shoe upper embodying the various features of my invention, parts being broken away and in section to more clearly 60 illustrate the details of construction, and

Fig. 2 is a top plan view of the sole and heel members detached from the shoe upper.

Referring now more particularly to the accompanying drawing, 5 designates a shoe 65 or boot upper; 6 designates the bottom thereof; and 7 designates depending side flanges or ribs forming recesses for receiving the sole and heel members 8 and 9 respectively. As clearly shown in Fig. 1 of 70 the drawing, the bottom 6 and the depending side ribs or flanges 7 are integral with the upper 5 to thus insure against the passage of water or moisture into the interior 75 of the shoe. The upper 5 may be made of any water-proof material, such as heavy "ducking," rubber or leather, and when leather or "ducking" is employed, the flanges or ribs 7 are integral with the upper, and the bottom 6 is secured thereto in 80 a water-proof seam.

The sole and heel members have their upper portions slightly reduced to fit within their respective recesses formed by the depending ribs 7, a shoulder or rib 10 being 85 formed by the reduced portion thereof which is of substantially the same thickness as the ribs 7. As best shown in Fig. 1, the ribs 7 have disposed therein a plurality of spaced apart apertures protected with eyelets 11 which are adapted to register with a plurality of apertures formed in a metal strip 12 adapted to cover the exterior of the ribs 7. The sole and heel members are secured in their respective recesses by means 90 of suitable fastening 13 which passes through the registered openings and eyelets of the strip 12 and ribs 7 to engage in the sole and heel members. This structure readily removably secures the sole and heel 95 members to the upper and permits their removal and the insertion of a new sole and heel member when the old one has become worn, thus permitting the use of the upper with a number of soles and heels.

100 The strip 12 may be formed at the toe portion with a slightly upwardly projected portion 14 for protecting the toe of the upper and preventing the same from being "kicked out." In order that the sole and heel members may be flexibly connected together at the instep of the shoe, I provide 110

a flexible spring strip 15 which has its ends embedded in the sole and heel members.

From the foregoing description taken in connection with the accompanying drawing, it will be at once apparent that I providing, it will be a shoe which will be comparatively cheap to manufacture, which will outlast the ordinary shoe of this type in that its soles and heels may be renewed from time to time, and one which will be absolutely water-proof in every sense of the word. It will also be apparent that the soles and heels may be made of wood fiber or any other material which will not wear out easily and still be comparatively light.

What I claim as my invention is:

1. A water-proof shoe comprising a flexible upper and a bottom portion integral therewith, depending portions depending from the upper at the union of said bottom portion therewith, and sole and heel members removably secured to the depending portions.

2. A water-proof shoe comprising an upper and integral depending side ribs at the lower end thereof forming sole and heel receiving recesses, a bottom portion closing

the bottom of said upper and integral therewith whereby the said upper is rendered water-proof, and sole and heel members removably disposed in said recesses.

3. A water-proof shoe of the class described comprising an upper having integral depending side ribs forming sole and heel receiving recesses, sole and heel members disposed in said sole and heel receiving recesses, and means passed through said side ribs and engaging the sole and heel members to secure the same in their respective recesses.

4. A water-proof shoe of the class described comprising an upper having integral depending side ribs forming sole and heel receiving recesses and having apertures therein, sole and heel members removably disposed in said recesses, a securing strip having apertures therein adapted to register with the apertures in the side ribs, and securing means passed through the registered apertures to secure the sole and heel members in their respective recesses.

In testimony whereof, I affix my signature.

LEO HOFMEISTER.
